US00D617787S

(12) **United States Design Patent**
Richardson et al.

(10) **Patent No.:** **US D617,787 S**
(45) **Date of Patent:** **** Jun. 15, 2010**

(54) **CASE**

(75) Inventors: **Curtis R. Richardson**, Fort Collins, CO (US); **John H. Loudenslager**, Phoenix, AZ (US); **Jamie L. Johnson**, Fort Collins, CO (US); **Adam Wibby**, Fort Collins, CO (US); **Jane Dulany**, Wellington, CO (US)

(73) Assignee: **Otter Products, LLC**, Ft. Collins, CO (US)

(**) Term: **14 Years**

(21) Appl. No.: **29/344,695**

(22) Filed: **Oct. 2, 2009**

(51) **LOC (9) Cl.** **14-03**

(52) **U.S. Cl.** **D14/250**

(58) **Field of Classification Search** D14/140, D14/142, 167, 217, 218, 240, 242, 248, 250–253, D14/299, 341–347, 440; D3/200–201, 215, D3/218–219, 226, 228, 269, 301, 272–273, D3/276, 294; D13/103, 107–108, 119; 220/4.02, 224/191, 240, 241, 245, 682–683; 248/206.2–206.4, 248/220.21, 279.1, 309.1; 361/679.3, 679, 361/56; 379/420.04, 426, 433.11, 446–447, 379/454, 455; 455/575.1, 575.6, 575.7, 575.8, 455/575.9; 190/100; 206/305, 320

See application file for complete search history.

CLAIM

The ornamental design for a case, as shown and described.

DESCRIPTION

FIG. 1 is an isometric view of a case showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line portions of the disclosure are for illustrative purposes only and form no part of the claimed design.

1 Claim, 7 Drawing Sheets
